UNITED STATES PATENT OFFICE.

CHARLES S. CLARK, OF NEW YORK, N. Y.

COMMODITY-ADVERTISING DEVICE.

Application filed March 10, 1923. Serial No. 624,189.

To all whom it may concern:

Be it known that I, CHARLES S. CLARK, a citizen of the United States, residing at New York, in the county of New York and State of New York, have invented a new and useful Improvement in Commodity-Advertising Devices, of which the following is a specification.

This invention relates to those devices which are designed for the purpose of advertising commodities and food products that are packed in glass jars.

Packing companies pack bacon, jam, jellies, fruits, candies and the like products in glass jars covered with metallic caps.

The object of this invention is to provide a very simple and cheap means which can be readily applied to the jars regularly used in trade for such purpose, and that may be connected with the ordinary electric light outlet for producing an illuminated package simulating the genuinely filled package.

This object is attained by providing for the standard jar a lining of paper or other fabric printed or otherwise ornamented with a representation of the particular goods as commonly packed in the jar and to which attention is desired to be called, and applying an electric lamp to the stock cap for that jar, in such manner that when the cap is sealed on the jar in the customary way the lamp globe will be within the jar and the screw base for the attachment of the electric light circuit will be on the exterior of the cap, so that an ordinary lighting circuit may be readily connected and when the current is turned on and the lamp is lighted the jar will appear to contain the regular goods illuminated.

In the accompanying drawings Figure 1 shows a side view of a package representing a well known brand of goods, made up according to this invention. Fig. 2 shows a central vertical section of the same.

The jar 1 is made of glass and is illustrated in a form regularly used in commerce in large quantities for containing bacon, jams, jellies and the like food products by a well known packing company. The cap 2 is stamped from sheet metal and is shown in

the shape of the stock cap provided for such jars. These jars have a shoulder 3 around the outside a little below the rim 4 and on this shoulder, when the jars are used for containing genuine goods, is a yielding gasket 5. The cap has a flaring skirt 6 that fits upon the gasket and when air is exhausted from the interior of the jar, as is common in sealing these jars, atmospheric pressure on the exterior of the cap causes the skirt 60 to compress the gasket and make a tight joint.

In carrying out this invention a lining 7 of paper or other fabric is shaped to fit within the jar. This lining is printed or 65 ornamented, desirably in colors, in any suitable way so as to represent the actual goods which are ordinarily packed in the jar. In the drawings the lining is designed to represent a quantity of bacon in the jar. Of 70 course the lining could be printed to depict any other desired commodity which is commonly found in the jar. The cap is perforated and fitted in the opening is an incandescent electric lamp base 8. The lamp is 75 arranged so that when the cap is on the jar the globe 9 will be within the jar and the screw threaded shell will be on the outside of the cap in position to receive a common form of attachment socket.

As stated the jar is one of the regular commercial jars used in large quantities for containing commodities and the cap is one of the regular stock caps provided for such jars. The lining pictures the goods that are ordinarily packed in the jars. When the lamp is lighted the package appears to be a regular commercial package with genuine goods illuminated. No special jars are required and no special caps are made necessary. 80 The common cap provided with the ordinary lamp can be applied to any of the jars of the type for which it is designed.

The invention claimed is:—

1. A device for advertising commodities 85 which comprises a glass jar, a lining fitted within the jar, said lining being ornamented to picture a contained mass of food, a metallic cap fitted upon and closing the jar, and an incandescent electric 100

lamp attached to and supported by the cap with the globe of the lamp inside of the lining and the threaded shell outside of the cap.

5. 2. A device for advertising commodities which comprises a glass jar, a paper lining fitted within the jar, said lining being orna-

mented to picture a contained commodity, a metallic cap fitted upon and closing the jar, and an incandescent electric lamp extending through and secured to the cap with the globe within the lining and the threaded shell of the lamp on the outside of the cap.

CHARLES S. CLARK,
